(57) **CLAIM**

The ornamental design for a covered beading design board, as shown and described.

DESCRIPTION

FIG. 1 is a perspective top view of the covered beading design board of the present invention with the cover in place over the board;

FIG. 2 is a perspective top view of the embodiment shown in FIG. 1, with the cover separated from the board;

FIG. 3 is a top plan view of the covered beading design board of FIG. 1 with the cover in place over the board, the bottom plan view is substantially identical;

FIG. 4 is a left side view of the covered beading design board of FIG. 1 with the cover in place over the board, the right side view is substantially identical;

FIG. 5 is the front side view of the covered beading design board of FIG. 1 with the cover in place over the board, the back side view is substantially identical;

FIG. 6 is a top plan view of the covered beading design board of FIG. 1, with the cover removed;

FIG. 7 is a left side view of the covered beading design board of FIG. 6 with the cover removed, the right side view is substantially identical;

FIG. 8 is the front side view of the covered beading design board of FIG. 6 with the cover removed, the back side view is substantially identical;

FIG. 9 is a bottom plan view of the covered beading design board of FIG. 1;

FIG. 10 is a top plan view of the cover of the covered beading design board of FIG. 1, the bottom plan view is substantially identical;

FIG. 11 is a left side view of the cover of the covered beading design board of FIG. 1, the right side plan view is substantially identical; and,

FIG. 12 is a front plan view of the cover of the covered beading design board of FIG. 1, the back side plan view is substantially identical.
